MATERNITY DRESS

Edna Christelman, Wantagh, N. Y.

Application February 19, 1958, Serial No. 49,696

Term of patent 3½ years

(Cl. D3—26)

I claim:

The ornamental design for a maternity dress, substantially as shown and described.
